LA FAYETTE LOUIS, OF PROVIDENCE, RHODE ISLAND.

Letters Patent No. 65,822, dated June 18, 1867; antedated June 11, 1867.

IMPROVEMENT IN MELODEONS.

The Schedule referred to in these Letters Patent and making part of the same.

TO ALL WHOM IT MAY CONCERN:

Be it known that I, LA FAYETTE LOUIS, of the city and county of Providence, in the State of Rhode Island, have invented an Improvement in Melodeons; and I do hereby declare that the following, taken in connection with the drawings which accompany and form part of this specification, is a description of my invention sufficient to enable those skilled in the art to practise it.

The present invention relates to the construction of tremolo-valves of melodeons, and to the method of applying such valves, and of bringing them into operation, and the drawing represents so much of a melodeon embodying my improvements as will enable the invention to be readily understood—

Figure 1 showing a plan of the melodeon case and the valves.

Figure 2, a cross-section through the front of the bellows.

Figure 3, a side view, and

Figure 4, an end view of the tremolo valve-board and valve.

Figure 5, a front view of that part of the case at which the direct-action valve is located.

a (see particularly fig. 2) denotes the melodeon-frame or case; *b* (fig. 2) the bellows; *c* the reed-board; *d* one of the reeds; *e* the valve-box or chamber, the bellows connecting with this box through openings *f*, over which openings, and within the box, is a long valve, *g*, which I term the "direct-action valve." This valve is held open in normal position, (as seen in fig. 2,) while when closed it shuts off communication (through the openings *f*) between the bellows and the valve-box and reeds above it. The bellows, operated in the usual manner by exhaustion or rarefaction of the air within them, draw down the air through the reeds and produce the required sounds. The tremolo-valve is seen at *h*, figs. 1, 3, and 4. This valve is hinged to the under surface of a valve-board, *i*, and opens and closes a valve-opening, *k*, through the valve-board, the valve playing in a passage or opening, *l*, (seen by dotted lines in fig. 1,) communicating with the bellows-chamber. The valve *h* is kept in normal position by means of a lever, *m*, fulcrumed in the valve-board as seen at *n*, (figs. 1 and 3,) and connected at *o* with the vibrating end of the valve, the opposite end of the lever having a long screw, *p*, (see figs. 1 and 3,) extending from it, upon the outer end of which screw is a weight, *q*, the gravity of which draws the valve against its seat. The extent of movement of the valve *h* is determined by means of two buttons *r*, upon the ends of adjusting-screws *s* (see figs. 1 and 3) which work through the valve-board, the valve opening more or less accordingly as the buttons are fixed at a greater or less distance from the valve-board by means of the screws.

In the operation of the melodeon the long or direct-action valve *g* is held normally open, as seen in fig. 2, by the upper end of a lever, *x*, (upon which the valve rests,) and a spring, *t*, acting upon said lever (see figs. 2 and 5.) The lower end of said lever extends down at the front of the bellows and into position where it is readily operated by a slight lateral movement of the knee of the performer. When he wishes to produce the tremolo, he presses the lower end of the lever, which depresses its upper end and allows the valve *g* to close by gravity. The action of the bellows must now draw the air from the reed-chamber through the tremolo-valve *h*, which by means of the weight applied thereto is caused to vibrate or pulsate and produce the desired tremulous effect. The adjustability of this weight, and its location, enable the valve to be readily adjusted to the power of the bellows, and in order to regulate the quickness of vibration of the valve, the buttons or stops which determine the extent of movement of the valve are made adjustable so as to regulate this length of vibration.

It will be observed that by applying the valve-board *i* immovably to the bellows-board, or secured to it by screws or other similar fastenings, and vibrating the valve through this board, (pivoting the lever directly in the valve-board,) and employing the auxiliary valve *g* for closing the direct passage of the air from the reeds to the bellows, in contradistinction to hinging the tremolo-valve in a valve-box or cover, and hinging this box so that its elevation the air passes directly through the passage beneath it without vibrating the tremolo. I am enabled to introduce the tremolo into instruments in which the space between the reed and bellows-boards is too shallow to otherwise allow of such introduction, except by increasing this depth, which increase is generally impracticable. By the common application, in order to have a proper distribution of air when the tremolo is not in action, the hinged box used would have to be built nearly as long as the key-board, in order

to allow the whole key-board to be influenced by the tremolo, making a very expensive construction constantly liable to get out of order, whereas in my arrangement, by employing a simple valve, *g*, as the direct-action valve, I get the desired distribution of air through the same, and obtain the tremulous action through a separate valve arrangement of only sufficient capacity to allow the interrupted air to pass through.

I claim combining, with a tremolo-valve, *h*, hinged directly to an immovable or fixed valve-seat, an auxiliary valve, *g*, for regulating the direct passage of the air from the reeds to the bellows, substantially as described.

I also claim, in combination with the valve *h*, the lever *m*, and its counterbalancing weight *q*, when this lever is pivoted or hung directly in or to the valve-board, substantially as set forth.

I also claim applying such weight to the lever by means of an adjusting-screw, substantially as set forth.

Also combining with the valve *g* the buttons *r*, made adjustable with respect to the valve-seat substantially as described.

Also combining with a tremolo-valve *h*, and a direct-passage valve, a lever extended down from the valve to such position that it may be operated by the knee or foot of the performer, substantially as set forth.

LA FAYETTE LOUIS.
